Attest;

Chancery B. McGee
Edw. Sumner

Inventor;

Andrew Tracy,

UNITED STATES PATENT OFFICE.

ANDREW T. MCCOY, OF BOSTON, MASSACHUSETTS, ASSIGNOR TO JOHN ANDERSON, OF NEW YORK, N. Y.

PRINTING-TELEGRAPH.

SPECIFICATION forming part of Letters Patent No. 431,987, dated July 8, 1890.

Application filed October 17, 1887. Serial No. 252,642. (No model.)

To all whom it may concern:

Be it known that I, ANDREW T. MCCOY, a subject of the Queen of Great Britain, residing at Boston, in the county of Suffolk and State of Massachusetts, have invented a new and useful Improvement in Printing-Telegraphs, of which the following is a specification, reference being had to the accompanying drawings.

10 My invention relates to the printing-machine of a printing-telegraph, and particularly to the means in such machine for inking; and it consists in the combination of an ink-tape with the platen or press roller and the type-wheel, and in the mechanism for operating said ink-tape, as hereinafter set forth, and specifically pointed out in the claims.

20 In the drawings, Figure 1 is a front view of so much of an electric printing-machine embodying my improvement as is sufficient to illustrate my invention. Fig. 2 is a side view of part of the same, one of the tape-wheels and the ratchet-wheel connected therewith being omitted in this figure.

25 On a shaft *a*, in fixed bearings *b*, I have shown a type-wheel *A*. The frame for supporting the type-wheel may, however, be that of any known electric printing-machine, and also the mechanism and apparatus for operating said wheel. The usual press-lever *B*, pivoted at *c* and bearing the armature *d* for the press-magnet, carries at or near the outer end a platen or press roller *e*. On shafts in fixed bearings or on studs *f*, fixed to the frame

30 *C*, I locate two rollers or tape-wheels *D* and *E*. To each of these tape-wheels and concentric therewith is fixed one of two ratchet-wheels *F* and *G*. A lever *H* is pivoted to the frame *C*, as at *g*, and has pivoted thereto at 35 *h* a pawl *I*, which is formed at the outer end and located between the ratchet-wheels, that it may engage with only one of them at a time, and with either of them, as required.

Pivoted at one end to the press-lever *B* at

i is a rod *J*, which is pivoted at the other end to the lever *H* at *j*. I fasten one end of a suitable tape *K* to one and the other end to the other of the tape-wheels *D* and *E*, so that when it is rolled upon one of these wheels it will be unrolled from the other. I prefer to have the tape-wheels located with reference to the press-roller, as shown, so that the tape will move lengthwise of this roller, and will pass over two fixed pins *k* or two rollers, which will keep the tape in proper relation to the press-roller.

The paper strip (a portion being shown at *l*) which is to be printed is carried over the press-roller in the usual manner and by mechanism which it is not necessary here to show.

In operation the pawl *I* is thrown over to engage with either of the ratchet-wheels, as desired. On each upward movement of the press-lever this pawl will move a ratchet-wheel, and the tape, properly saturated with ink, will be wound upon the tape-wheel fixed to this ratchet-wheel and be unwound from the other tape-wheel, passing under the type-wheel, so as to present a fresh surface to be acted upon by the type.

70 I claim as my invention—

1. In an electric printing-machine, the combination of a press-lever, a lever *H*, a rod connecting said levers, two tape-wheels, a ratchet-wheel fixed to each tape-wheel, a pawl pivoted to the lever *H* for operating the ratchet-wheels, and guide-pins for the tape, substantially as specified.

2. The combination of the press-lever, a lever *H*, a rod *J*, connecting these two levers, a pawl *I*, two tape-wheels *D* and *E*, and two ratchet-wheels *F* and *G*, substantially as specified.

75 ANDREW T. MCCOY.
